US00D941930S

(12) **United States Design Patent** (10) **Patent No.:** **US D941,930 S**
(45) **Date of Patent:** **** Jan. 25, 2022**

(54) **ELECTRIC SCOOTER**

(71) Applicant: **RAZOR USA LLC**, Cerritos, CA (US)

(72) Inventors: **Robert Hadley**, Yorba Linda, CA (US);
Robert Chen, San Marino, CA (US)

(73) Assignee: **Razor USA LLC**, Cerritos, CA (US)

(**) Term: **15 Years**

(21) Appl. No.: **29/774,556**

(22) Filed: **Mar. 17, 2021**

Related U.S. Application Data

(63) Continuation of application No. 29/637,724, filed on Feb. 21, 2018, now Pat. No. Des. 914,102, which is a continuation of application No. 29/587,133, filed on Dec. 9, 2016, now Pat. No. Des. 811,489, which is a continuation of application No. 29/553,287, filed on Jan. 29, 2016, now Pat. No. Des. 774,145, which is a continuation of application No. 29/527,262, filed on May 18, 2015, now Pat. No. Des. 748,738, which is a continuation of application No. 29/500,274, filed on Aug. 22, 2014, now abandoned, which is a continuation of application No. 29/472,328, filed on Nov. 11, 2013, now abandoned, which is a continuation of application No. 29/415,919, filed on Mar. 15, 2012, now Pat. No. Des. 693,414.

(57) **CLAIM**

The ornamental design for an electric scooter, as shown and described.

DESCRIPTION

FIG. 1 is a perspective view showing top, left and rear sides of an electric scooter.

FIG. 2 is a right side view of the electric scooter of FIG. 1.

FIG. 3 is a left side view of the electric scooter of FIG. 1.

FIG. 4 is a front view of the electric scooter of FIG. 1.

FIG. 5 is a rear view of the electric scooter of FIG. 1.

FIG. 6 is a top view of the electric scooter of FIG. 1; and,

FIG. 7 is a bottom view of the electric scooter of FIG. 1.

Where utilized, the broken lines show portions of the electric scooter that form no part of the claimed design.

1 Claim, 5 Drawing Sheets
